Primary Examiner — Eric Goodman*Assistant Examiner* — Megan M Majcher Hartnett(74) *Attorney, Agent, or Firm* — Klarquist Sparkman, LLP(57) **CLAIM**

I claim the ornamental design for a display screen with graphical user interface, as shown and described.

DESCRIPTION

The FIGURE is a front view of a display screen with graphical user interface showing the new design.

The dash-dot-dash and evenly spaced broken lines in the drawings represent portions of the display screen with graphical user interface that form no part of the claimed design.
